UNITED STATES PATENT OFFICE.

LOUIS F. CLEMENTS, OF KANSAS CITY, MISSOURI.

ADVERTISING NOVELTY.

Application filed July 31, 1925. Serial No. 47,334.

To all whom it may concern:

Be it known that I, LOUIS F. CLEMENTS, a citizen of the United States, residing at Kansas City, in the county of Jackson and 5 State of Missouri, have invented a new and useful Advertising Novelty, of which the following is a specification.

This invention relates to advertising novelties and the object thereof is to provide a 10 cheaply constructed attractive device of this character having means for detachably supporting an advertising card or other indicia.

With the foregoing and other objects in view which will appear as the description 15 proceeds, the invention resides in the combination and arrangement of parts and in the details of construction hereinafter described and claimed, it being understood that changes in the precise embodiment of the 20 invention herein disclosed may be made within the scope of what is claimed without departing from the spirit of the invention.

In the accompanying drawings:—

Figure 1 represents a plan view of the 25 blank from which this novelty is constructed;

Figure 2 is a similar view showing the completed article;

Figure 3 is a side elevation thereof; and

30 Figure 4 is a transverse section taken on the line 4—4 of Figure 3.

The blanks from which these articles are made are struck out in the form of a fire fly as shown in Figure 1 in which a substantially 35 ovate body member 1 has a head 2 at one end and a rectangular extension at the other end which is designed to be rolled to form

the tail member 5 of Figure 2. Extending laterally from the side edges of the body are tongues 4 which are designed to be bent 40 inward on the completed device to form card supports as shown clearly in Figures 3 and 4.

The blank shown in Figure 1 is struck out of thin sheet metal and is designed to be 45 placed in a die to have the lines 6 and 7 formed thereon and the square end 3 rolled to form the tail member 5 and the body formed into substantially semi-cylindrical shape as shown at 8 in Figures 3 and 4. The 50 tail 5 is preferably coated with luminous paint to render it clearly visible in the dark. This device is intended to represent a fire fly or lightning bug and the tongues 4 which are bent inwardly under the body 55 portion thereof serve as a frame to hold a small card 10 designed to contain advertising matter.

By constructing this article as shown and described it is made extremely light and can 60 be cheaply manufactured and the cards 10 may be readily removed and others substituted when desired.

I claim:—

A device of the class described struck 65 out from a sheet of metal and bent to form an elongated body open at its lower face and having inturned card securing clamping fingers along its side edges and with a rolled tail at one end and a head at the other. 70

In testimony that I claim the foregoing as my own, I have hereto affixed my signature.

LOUIS F. CLEMENTS.
